CIGARETTE HOLDERS

Hans Lowenthal, London, England, assignor of one-half to Colibri Lighters Limited, London, England, a British company

Application June 6, 1955, Serial No. 513,529

Claims priority, application Great Britain June 30, 1954

9 Claims. (Cl. 131—182)

Cigarette holders which contain replaceable filters are well known, but they suffer from several disadvantages. The filter elements frequently fit tightly in the holder and when they are completely saturated with tarry matter their removal with the fingers is a somewhat unpleasant operation particularly with filters which are not housed in plastic or glass, this latter type being expensive to manufacture. It is also usually necessary to dismantle the holder to examine the filter element at intervals to see when renewal is necessary.

The present invention provides a cigarette holder which effectively overcomes both the disadvantages, and one which may also be arranged to eject the cigarette stub.

According to the invention, the cigarette holder part has an internal chamber for a filter element, a detachable mouthpiece and means for ejecting the filter element from the chamber through the mouthpiece end of the holder part when the mouthpiece is detached. The means for ejecting the filter element preferably comprises a plunger fitted within the chamber which plunger may be moved against the action of a spring to eject the filter element.

According to further features of the invention, the chamber for the filter element is provided in a transparent exterior portion which is normally disposed within an opaque tube, but which may be moved against the action of a spring out of the opaque tube to examine the condition of the filter element. Also the plunger for ejecting the filter element extends through the holder part to a location immediately behind the end of the cigarette inserted into the holder part for ejecting the cigarette stub.

An example of a cigarette holder, according to the invention is illustrated in the accompanying drawing in which:

Figure 1 is a side elevation of the entire holder;

Figure 2 is a longitudinal section through the holder shown in Fig. 1 in its normal position;

Figure 3 is a longitudinal section similar to Figure 2, but showing the plunger moved forwardly to eject the cigarette stub;

Figure 4 also is a longitudinal section of the holder part similar to Figure 2 but with the chamber for the filter element shown partially in elevation withdrawn from the opaque tube;

Figure 5 shows a longitudinal section of the holder similar to Figure 2 with the mouthpiece removed and the plunger operated to eject the filter element;

Figure 6 is an end elevation of the holder looking in the direction of the arrow VI of Figure 2.

Figure 7 is a cross-section of the holder on the line VII—VII looking toward the right in Figure 4.

Referring to the drawing, the cigarette holder has a body part 1 and a hollow transparent part 2 containing a filter element 3. The hollow transparent part 2 is normally disposed within an opaque tube 4 extending rearwardly from the body part 1. A mouthpiece 5 is screwed into the rear end of the hollow transparent part 2. A

2

plunger comprising a tube 6, with pistons 7 and 8 fixed on its forward and rear ends, respectively is also located within the opaque tube 4. The tube 6 extends through a hole 9 in a partition 7a extending across the forward end of the hollow transparent part 2, and through a hole 10 in the rear end 11 of the body 1. Coiled compression springs 12 and 13 surround the tube 6 and bear respectively against the piston 7 and the partition 7a in the transparent hollow part 2. The adjacent rear and forward ends of these springs, away from the piston 7 and the hollow part 2, abut against the end 11 of the body part 1.

The forward end of the body part 1 into which a cigarette has been inserted has a metal lining 14 which is a push fit therein and which is formed with two longitudinally extending ribs 15 and 16. The piston 7 has two grooves 17 and 18 engaging over the ribs 15 and 16. The piston 7 may thus slide axially along the length of the ribs 15 and 16, but while in engagement with the ribs cannot rotate.

The operation of the holder is as follows:

To eject a cigarette stub the body part 1 is held in one hand and the mouthpiece 5 is pressed forwardly with the other hand. The piston 8 is thus pressed forwardly by the filter element 3 which also bears against the mouthpiece. The tube 6 and the piston 7 are carried forwardly with the piston 8 until the piston 7 bears against the rear end of the cigarette stub and ejects it forwardly. This movement takes place against the action of the spring 13 which is compressed between the partition 11 and the forward end of the hollow part 2. On releasing the mouthpiece the spring 13 then returns the parts of the holder to their normal positions.

To examine the condition of the filter element 3, the body part of the holder 1 is again held in one hand and the mouthpiece 5 is pulled with the other hand. The hollow transparent part 2 is thus moved rearwardly and carries with it the piston 8, the tube 6 and the piston 7. When the hollow transparent part 2 is moved sufficiently outside the opaque tube 4, the filter element can be examined. This movement takes place against the action of the spring 12 which is compressed between the partition 11 and the piston 7 as shown in Figure 4 and thus returns the parts to their normal positions when the mouthpiece is released.

To eject the filter element 3 from the hollow transparent part 2, the mouthpiece 5 is again pulled rearwardly with respect to the body part 1 against the action of the spring 12 in the same way as for examining the condition of the filter, but the movement is continued until the grooves 17 and 18 in the piston 7 are moved out of engagement with the ribs 15 and 16, and the mouthpiece is then rotated in one direction or the other. The tube 6 and the hole 9 fit each other and are both of slightly oval or other non-circular section as shown in Figure 7, but the hole 10 has a clearance so that the tube can rotate in it. The tube 6 and the piston 7 are, therefore, rotated together with the mouthpiece 5. On release of the mouthpiece 5, the piston 7 cannot move forwardly because the grooves 17 and 18 are no longer coincident with the ribs 15 and 16 and the piston, therefore, bears against the rear ends of the ribs.

The mouthpiece is next unscrewed from the hollow transparent part 2 which is then pushed forwardly into the opaque tube 4 against the action of the spring 13 from the position shown in Figure 4 to that in Figure 5. The piston 7 and the tube 6 and piston 8 being locked in position longitudinally relative to the body part, the piston 8 bears against the forward end of the filter element 3 and pushes it out of the hollow transparent part 2 as the latter is moved forwardly. On release of the hollow transparent part 2, it is moved rearwardly by the

spring 13 until the piston 8 is again fully retracted. A new filter element may then be inserted and the mouthpiece replaced.

The mouthpiece is again rotated until the grooves 17 and 18 are coincident with the ribs 15 and 16 whereupon the piston 7 is moved forwardly by the spring 12 and the parts of the holder are returned to their normal positions.

Any other means instead of the ribs 15 and 16 may of course be used to lock the piston 7 against axial movement so that the piston 8 may be moved within the hollow transparent chamber 2 to eject the filter, but the ribs 15 and 16 have the additional advantage that they also greatly improve the grip of the cigarette holder on a cigarette and are shaped for this purpose.

I claim:

1. In a cigarette holder, a body for holding a cigarette, said body having a chamber for containing a filter element, a mouthpiece detachably secured to said body, means disposed within said body for ejecting said filter element from said chamber through the end of said body adjacent said mouthpiece when said mouthpiece is detached, and means disposed within said body for ejecting said cigarette from the end of said body remote from said mouthpiece.

2. In a cigarette holder, a body for holding a cigarette, an opaque tube having one end fixed to said body, a hollow transparent member for containing a filter element disposed within the other end of said opaque tube, a smoke conducting tube having one end slidably in said body and the other end slidably in said transparent member, a mouthpiece detachably secured to said transparent member, and spring means surrounding said smoke conducting tube and yieldably holding said transparent member in said opaque tube, said smoke conducting tube being selectively movable in said body to eject said cigarette from the end of said body remote from said mouthpiece and selectively movable in said transparent member for either ejecting said filter element from the end of said transparent member adjacent said mouthpiece when said mouthpiece is detached or for inspecting said element in said transparent member.

3. In a cigarette holder, a body part for holding a cigarette, a plunger slidably mounted in said body part for ejecting said cigarette therefrom, said plunger having a portion projecting from said body part, a hollow tubular member for containing a filter element having one end mounted on said projecting portion of said plunger, a spring surrounding said projecting portion of said plunger, and a mouthpiece detachably secured to the other end of said hollow member, said hollow tubular member being slidable on said projecting portion of said plunger against the action of said spring for ejecting said filter element from said other end of said hollow tubular member when said mouthpiece is detached.

4. In a cigarette holder as claimed in claim 3, further comprising an opaque tube fixed to said body part and extending around the projecting portion of said plunger and said hollow tubular member, said spring yieldably holding said hollow member within said opaque tube.

5. In a cigarette holder, a body part for holding a cigarette, a first piston mounted in said body part, a smoke conducting tube having one end fixed to said first piston, a second piston fixed on the other end of said smoke conducting tube, a hollow tubular member for containing a filter element having one end mounted on said second piston, a mouthpiece detachably secured to the other end of said hollow tubular member, a first coiled spring surrounding said smoke conducting tube and abutting said body part and said hollow tubular member, said first piston being slidable in said body part against the action of said first spring to eject said cigarette from said body part and said second piston being slidable in said hollow tubular member against the action of said first spring to eject said filter element from said other end of said hollow tubular member when said mouthpiece is detached.

6. A cigarette holder as claimed in claim 5, further comprising an opaque tube fixed to said body part and extending around said smoke conducting tube and said hollow tubular member and a second coiled spring surrounding said smoke conducting tube within said body, said second spring yieldably holding said hollow tubular member in said opaque tube.

7. A cigarette holder as claimed in claim 3, said body part having at least two longitudinally extending internal ribs, and said plunger having a smoke conducting tube, a piston slidable in said body part fixed on one end of said smoke conducting tube, said piston having at least two longitudinal grooves, each of said grooves being adapted to be engaged over one of said ribs and said ribs being shaped to provide a firm grip for a cigarette.

8. A cigarette holder as claimed in claim 5, further comprising means operable to prevent axial movement of said first piston in said body.

9. A cigarette holder as claimed in claim 8, wherein said means operable to prevent axial movement of said first piston in said body comprise at least two ribs extending longitudinally of said body and at least two longitudinal grooves in said first piston, each of said grooves being adapted to be engaged over one of said ribs, said first piston being slidable beyond the ends of said ribs and rotatable whereby said first piston is engaged with the ends of said ribs to lock said first piston against axial movement.
